UNITED STATES PATENT OFFICE.

MICHAS HENDERSON, OF JEWEL, IOWA.

VARIABLE-IMPEDANCE COIL.

Application filed July 13, 1925. Serial No. 43,381.

The object of my invention is to provide a variable impedance, which may be either inductive or non-inductive and which is simple, durable and inexpensive.

5 A further object is to provide an impedance which is uniformly adjustable throughout its range and, therefore, does not have the disadvantage of the usual impedance which is adjustable by steps.

10 Still a further object is to provide impedance coils, so wound that upon compression, the coils thereof will be shorted in proportion to the amount of compression, thereby reducing the impedance of the coils.

15 Still a further object is to provide a simple and efficient means for accomplishing the compression of the impedance coils.

With these and other objects in view, my invention consists in the construction, arrangement and combination of the various parts of my device, whereby the objects contemplated are attained, as hereinafter more fully set forth, pointed out in my claim, and illustrated in the accompanying drawings,

25 in which:

Figure 1 is a top, plan view of my impedance device.

Figure 2 is a side elevation of the same, showing the coils released.

30 Figure 3 is an end elevation of the same, showing the coils partly compressed.

Figure 4 is a diagrammatic view of my device and an electric motor illustrating one way in which it can be utilized.

35 In the accompanying drawing, I have used the reference numeral 10 to indicate generally, a core which can be made of soft cast iron or be of laminated construction.

A base 11 may be provided on the lower, 40 horizontal bar of the core for convenience in fastening my device to a suitable support.

Pads 12 are formed on the core 10, and have on their upper surfaces, insulating washers 13. The vertical bars of the core 45 10 have insulating tubes 14 thereon.

A compressor bar 15 extends from one vertical bar to the other of the core 10 and has holes 16 which are substantially the same size as the outside diameter of the tubes 14.

50 It will thus be seen that the bar 15 is slidable vertically on the tubes 14.

The bar 15 has its under surface insulated by the insulating strip 17.

55 For adjusting the compressor bar 15, I provide a rod 18 journaled in the upper

and lower horizontal bars of the core 10, as at 19 and 20. A flange 21 and a shoulder 22 prevent endwise movement of the rod 18.

A portion 23 of the rod 18 is screw threaded, and coacts with an internally screw threaded boss 24 on the compressor bar 15. A crank 25 is secured to the upper end of the rod 18.

From the construction of the parts just described, it will be seen that rotation of the rod 18 in one direction will cause the bar 15 to descend while a reverse rotation will cause the bar 15 to ascend.

Interposed between the pads 12 and the compressor bar 15 are impedance coils 26 and 27, the lower ends of which are secured to binding posts 28 and 29.

The upper ends of the coils 26 and 27 are connected together, as at 30. The binding posts 28 and 29 extend through insulating bushings 33 as shown in section in Figure 2. They are supported by an ear 34 extending from each pad 12.

The connection 30 is against the insulation 17, and clears the boss 24, as shown in dotted lines in Figure 1.

It will be seen that the coils 26 and 27 are completely insulated from the core 10.

It will be noted by referring to Figure 2, that the successive turns of the reactance coils 26 and 27 are spaced farther from each other at the bottom of the coils than at the top. The purpose of this is so that as the bar 15 is moved downwardly, the wire of the coils will begin contacting at the top of the coils and as the bar 15 descends, the contact portion will increase, thereby shorting more and more of the upper portion of the coils, consequently cutting down their reactance until the coils are completely compressed and shorted and practically no resistance is encountered by the current passing therethrough.

In Figure 3, the portion from 35, up, 100 is shorted and the reactance encountered is the sum of the reactances in the two coils 26 and 27 from 35 down.

It is apparent that my device can be used in a great variety of circuits and for 105 all purposes, where a variable reactance is required. For illustration, I have shown it in circuit with a motor in Figure 4.

The feed wire 36 is connected to my impedance and a lead 37 connects the impedance to the motor 38 and the circuit is completed through the feed wire 39.

If a non-inductive resistance is required, the core 10 may be of insulating material, thereby eliminating the inductive effect of an iron core.

- 5 It will be seen that I have provided a simple, variable resistance and an efficient means for adjusting it.

I have eliminated the "jumpy" effect of a rheostat having contacts which are connected together by resistance units, and are thus adjustable by "steps". I have also entirely eliminated arcing contacts and their destructive effect.

10 For different requirements, finer wire or a greater quantity may be used for designing the coils 26 and 27 for higher resistance. The pitch of the threads 23 may vary for obtaining a coarser or finer adjustment per revolution of the crank 25.

15 20 Some changes may be made in the con-

struction and arrangement of the various parts of my invention, without departing from the real spirit and purpose of my invention, and it is my intention to cover by my claim, any forms of structure or use of 25 mechanical equivalents, which may be reasonably included within its scope.

I claim as my invention:

An adjustable impedance coil comprising a core, a coil of resistance wire of uniform 30 diameter wound thereon and having one end fixed relative thereto and the other end adapted to slide thereon, the pitch of said coil uniformly varying from end to end thereof, means for moving the free end of 35 said coil of resistance wire along said core whereby the adjacent turns of said coil are successively closed and the resistance of said coil uniformly reduced.

MICHAS HENDERSON.
